CONTAINER

John G. Bell, Brooklyn, N. Y.

Application April 4, 1942, Serial No. 437,650

7 Claims. (Cl. 229—4.5)

This invention relates to a new and useful improvement in containers made of paper or other sheet material, and in particular, to containers of this character intended principally for holding various semi-fluids, such as ice cream as it comes from the freezer, semi-solids and solids. Some of the important features of the container of this invention are a body composed of two sleeves of paper or other sheet material, one fitting snugly within the other, made of the same or different kinds and weights of material, a bottom, and, usually, a top. All of these parts are of extremely simple shapes, easily and inexpensively produced and assembled. Aside from the body sleeves, the edges of each of which are overlapped and fastened together by adhesive or stapling, the entire container can be assembled without the use of adhesive or metallic parts. The double-walled construction produced by two separate sleeves, one within the other, not only provides a structure of adequate rigidity, and considerable insulating merit, but one which is substantially puncture-proof in that the outer sleeve can be damaged without affecting the inner. The double-sleeve construction also permits the use of two different materials, for example, a high-grade paper for the inner sleeve, suitable for contact with food, and a less expensive outer sleeve for strength, etc. In short, this construction gives the greatest possible latitude in the nature of the inner and outer sleeves, so that the container can be adapted for the greatest number of uses at a minimum of cost.

One form of the invention is shown in the drawings, of which:

Figure 1 is an illustration in perspective of a container complete;

Figure 2 is a similar illustration of the top of this container;

Figure 3 is a similar view of the bottom of this container;

Figure 4 illustrates diagrammatically the blank from which the outer sleeve of the container is made;

Figure 5 is a similar illustration of the blank from which the inner sleeve is made;

Figures 6 and 7 illustrate, respectively, the outer and inner sleeves after the folding of the top and bottom edges have been completed;

Figures 8 and 9 illustrate, respectively, the inner and outer sleeves in collapsed condition for shipment or storage;

Figure 10 is a section of a fragment of the outer sleeve along the line 10—10 of Figure 8;

Figure 11 is a section of a fragment of the

lower part of the inner sleeve on the line 11—11 of Figure 9;

Figure 12 is an illustrated sectional view showing how the bottom is inserted into and positioned in the inner sleeve;

Figure 13 is a similar view illustrating the initial position of the top of the container;

Figure 14 is a sectional view illustrating the manner in which the outer sleeve is slipped over the inner sleeve and the top;

Figure 15 is also a sectional view showing the outer sleeve in its final position with respect to the inner sleeve and the top; and

Figure 16 is a section of the container along the line 16—16 of Figure 15.

The blanks from which the inner and outer sleeves are made are shown in Figures 4 and 5. As will be seen the shape of each is such that when edges 4 and 5 and 6 and 7, respectively, 20 are overlapped and secured by gluing or stapling, tapered sleeves with tops and bottoms in parallel planes result.

As shown in Figure 5, the inner face of inner sleeve 2 is provided with parallel scorings 8 and 9 adjacent its lower edge, so spaced from the edges and from each other that the edge may be folded upon scoring 8 and then again upon scoring 9 to make a double fold 10, upon the inside of the sleeve, as shown in Figures 7, 9, 11 and 12. A third scoring 9a may also be included, if desired, positioned just above the double fold 10 into which the bottom can be snapped.

Double fold 10 is the major support for the bottom 11 of the container. This bottom may consist of the disk 11, which is simply slipped into the upper end of inner sleeve 2, as shown in Figure 12 in dot and dash lines, and forced downwardly until it rests upon the double fold 10. If scoring 9a is included, the diameter of the bottom 11 should be slightly larger so that it will extend into the scoring by which it will be held against accidental displacement.

The outer sleeve 1 is provided with a pair of scorings 13 and 14 similar to those already described, but located at the top instead of at the bottom, as in the case of the inner sleeve. These scorings 13 and 14 permit of the inward folding of the upper edge of the outer sleeve to make a double fold 15, similar to double fold 10.

Before the outer sleeve 1 is positioned over the inner sleeve 2, the inner sleeve with the bottom in place, as shown in Figure 12, may be filled with whatever material it is to contain, which may be leveled off by simply passing a scraper across its top.

Top 16 of the container consists, preferably, of a disk 17 having a circular scoring 18, the diameter of which corresponds to that of the top of inner container 2, and an outwardly-extending skirt 19 bent downwardly as shown in Figure 2. This top 16 is placed upon the top of inner sleeve 2, edge down as shown in Figure 13, and then the bottom of outer sleeve 1 is passed over it as shown in Figure 14.

As outer sleeve 2 moves downwardly its decreasing diameter will cause it to engage skirt 19 of top 16, forcing it towards the inner sleeve until, when outer sleeve 1 comes to rest in close contact with inner sleeve 2, edge 19 of the top will be held tightly between the two sleeves and also against the top of inner sleeve 2 by the doubly-folded upper edge 15 of outer sleeve 1, as shown in Figure 15. Also the lower end of outer sleeve 1 will then have been forced over the bead produced by scoring 9a so that this end of the outer sleeve is also in very tight contact with the inner sleeve since the bead produced by scoring 9a cannot give appreciably because of the opposition of bottom 11, which, as already described, snugly fits into scoring 9a. In this way the inner and outer sleeves, which as already stated, are so proportioned as to have close frictional fit with each other when assembled, are substantially locked together at the upper end by the interposing skirt 19 of top 17, and at the lower end by outwardly-projecting bead produced by scoring 9a reinforced by bottom 11. Conversely, the engagement of bottom 11 with scoring 9a is made more secure by the inward pressure of outer sleeve 2 against the bead, resulting from this scoring.

In assembling the sleeves 1 and 2 it is preferable to locate the overlapped ends 4 and 5 of sleeve 1 opposite the overlapped ends 6 and 7 of the sleeve 2, as illustrated in Figure 16. This positioning of these overlapping ends is not absolutely necessary, but when heavy substances are packed in the completed container, the resistance of the container to bursting strains is greatly increased.

The container is now complete, the frictional engagement between the inner and outer sleeves and between these sleeves and the top makes it unnecessary to fasten the two sleeves together. The result is a double-walled container, all of the parts of which are assembled without gluing or other attachment with the exception of the overlapped edges of the sleeve blanks already described, which must be attached together in order to form the sleeves.

Although a container of this character may not be absolutely liquid-tight, it is admirably adapted for holding all sorts of solids, semi-solids and even semi-liquids, such as ice-cream as it comes from the freezer. It may be made absolutely liquid-tight, if desired, by coating it with paraffine or other suitable material, without affecting its construction or the general method of assembly.

For convenience in storing and shipping sleeves 1 and 2 may be flattened as shown in Figures 8 and 9. With this in mind they may be provided with scorings 29 and 30 spaced 180 degrees apart, which will act as hinges and insure that the flattening will be effectively accomplished without damage to the sleeves.

I claim:

1. A container of paper or similar sheet material, comprising an inner sleeve having an inwardly-folded bottom edge, an outwardly-extending groove in the inner surface of said inner sleeve immediately above the top of said folded bottom edge, a bottom supported upon said folded

bottom edge and projecting into said groove, a top supported upon the top of said inner sleeve, and an outer sleeve enveloping said inner sleeve in secure frictional engagement therewith and passing over a bead on the exterior of said inner sleeve opposite the before-mentioned groove in said inner sleeve, said outer sleeve having an upper edge folded inwardly so that it makes contact with said top to lock it in position.

- 10 2. A container of paper or similar sheet material, comprising an inner sleeve having a doubly and inwardly folded bottom edge, an outwardly-extending groove in the inner surface of said inner sleeve immediately above the top of said folded bottom edge, a bottom supported upon said folded bottom edge and projecting into said groove, a top supported upon the top of said inner sleeve, and an outer sleeve enveloping said inner sleeve in secure frictional engagement therewith and passing over a bead on the exterior of said inner sleeve opposite the before-mentioned groove in said inner sleeve, said outer sleeve having an upper edge folded doubly and inwardly so that it makes contact with said top to lock it in position.
- 15 3. A container of paper or similar sheet material, comprising an outer sleeve having a doubly and inwardly-folded bottom edge, an outwardly-extending groove in the inner surface of said inner sleeve immediately above the top of said folded edge, a bottom supported upon said folded bottom edge and projecting into said groove, a top supported upon the top of said inner sleeve and having a downwardly-directed skirt in engagement with the outside of said inner sleeve,
- 20 35 an outer sleeve enveloping and in close frictional engagement with said inner sleeve and with the skirt of said top and also passing over a bead on the exterior of said inner sleeve opposite the before-mentioned groove of said inner sleeve, said outer sleeve also having a doubly and inwardly-folded upper edge, the bottom of which rests upon the top to additionally secure it in position.

4. A container as claimed in claim 1, in which each sleeve is provided with two opposed longitudinal scorings upon which they can be flattened.

5. A container as claimed in claim 2, in which each sleeve is provided with two opposed longitudinal scorings upon which they can be flattened.

6. A container of paper or similar sheet material, comprising an inner sleeve, the longitudinal edges of which are overlapped and attached together, said inner sleeve also having an inwardly-folded bottom edge, an outwardly-extending groove in the inner surface of said inner sleeve immediately above the top of said folded bottom edge, a bottom supported upon said folded bottom edge and projecting into said groove, a top supported upon the upper end of said inner sleeve, an outer sleeve enveloping said inner sleeve in secure frictional engagement therewith, the longitudinal edges of said outer sleeve being overlapped and attached together, said outer sleeve passing over a bead on the exterior of said inner sleeve opposite the before-mentioned groove of said inner sleeve, said overlap of said outer sleeve being positioned substantially opposite the overlap of said inner sleeve, said outer sleeve also having an upper edge which is folded inwardly so that it makes contact with said top to lock it in position.

7. A container of paper or similar sheet material, comprising an inner sleeve, the longitudinal edges of which are overlapped and attached to-

gether, an inner sleeve also having an inwardly and doubly folded bottom edge, an outwardly-extending groove in the inner surface of said inner sleeve immediately above the top of said folded bottom edge, a bottom supported upon said folded bottom edge and projecting into said groove, a top supported upon the upper end of said inner sleeve, an outer sleeve enveloping said inner sleeve in secure frictional engagement therewith, the longitudinal edges of said outer sleeve being over-

lapped and attached together, said outer sleeve passing over a bead on the exterior of said inner sleeve, said overlap of said outer sleeve being positioned substantially opposite the overlap of said inner sleeve, said outer sleeve also having an upper edge which is inwardly and doubly folded so that it makes contact with said top to lock it in position.

JOHN G. BELL.
